UNITED STATES PATENT OFFICE.

ADRIAN D. NICHOLS, OF ST. LOUIS, MISSOURI, ASSIGNOR OF ONE-HALF TO OSCAR W. HOOPPAW, OF ST. LOUIS, MISSOURI.

MACHINE FOR CORRECTING THE MALADJUSTMENT OF THE ATLAS AND AXIS.

1,233,496.

Specification of Letters Patent.

Patented July 17, 1917.

Application filed June 19, 1916. Serial No. 104,389.

To all whom it may concern:

Be it known that I, ADRIAN D. NICHOLS, a citizen of the United States, and a resident of the city of St. Louis and State of Missouri, have invented a new and useful Machine for Correcting the Maladjustment of the Atlas and Axis, the first two spinal vertebrae of the neck, of which the following is a specification.

10 The object of the invention is to increase the supply of blood to the brain and spinal cord through the vertebral artery, which is diminished in case the atlas and axis are not in correct alinement. Incorrect alinement, 15 or mal-adjustment, of the atlas and axis also affects the circulation through the internal carotid artery.

This invention relates particularly to a mechanical device for correcting the mal-adjustment of the atlas and axis, and for securely holding these two vertebrae (atlas and axis) by permitting a nodding motion of the head of the patient, so as to correctly adjust the atlas and axis to their normal relation with the skull and spine.

Further details of this invention appear below in connection with the description of the device illustrated in the accompanying drawings for carrying out the theory, and 30 what the invention consists in is more particularly defined in the appended claims.

In the drawings, where the same reference characters are used to designate like parts in the several views,

35 Figure 1 is a front view of a suitable device or apparatus for performing the invention;

Fig. 2 is a side view, and Fig. 3 is a plan view of the same, the head strap being re-40 moved in Fig. 3;

Fig. 4 is a side view, and Fig. 5 is an end view of an adjustable bracket and finger, forming part of the device; and

Fig. 6 is a cross-section of a portion of 45 the adjusting mechanism for each pair of brackets.

The apparatus is mounted on a portable frame 10 which may be placed against the end of a suitable support or table, and secured thereto by hooks or clamps. The portable frame 10 has a shelf 11 extending across its front, upon which is mounted suitable apparatus for securely holding the

bones of the neck and head. This apparatus comprises a vertical slide 12, which is adjustable up and down by means of a vertical screw operated by a hand wheel 13. Upon the vertical slide 12 is slidably arranged a cross slide 14, which is adjustable toward and away from the table by means of a horizontal screw, operated by a crank handle 15.

The cross slide 14 supports two sets of clamping fingers for engaging the vertebrae of the neck. The forward set 16 of clamping fingers is adapted to engage over or around or any other way necessary to hold firmly the lateral processes of the atlas (which is the first vertebra of the spinal column) upon which the skull pivots and is supported. A second set 17 of fingers engage over or around or any other way necessary to hold firmly the lateral processes of the axis, which is the second vertebra of the spinal column.

Differently shaped fingers may be used to conform with the shape and arrangement of the vertebrae of the patient, and the ends of the fingers may be covered with pads or rubber, or other suitable material.

The head rest 18 is pivotally mounted on arms 19. The head rest has an adjustable pad 20, upon which the back of the head of the patient rests, also an adjustable clamping plate 21 for engaging the top of the head to position it centrally in the frame. An adjustable strap 22 with its ends engaging slots in the sides of the frame, is adapted to be drawn tightly over the top of the head or forehead. These three clamping means hold the head securely in place in the frame. The pad 20 and plate 21 are mounted by means of ball and socket, or double universal joints, upon the ends of the adjusting screws 23, so as to be free to accommodate themselves to the shape of the head.

The supporting pad 20 and strap 22 are adjustable horizontally toward and away from the fingers 16. The supporting screw 100 for the pad 20 is mounted in a sleeve 24, which can be moved along a slot in the depending arm 25 of the frame, in which it is mounted, and can be clamped in any desired position of adjustment by means of the 105 knurled nut 26. The head rest is supported in

its normal horizontal position by means of a pivoted arm 27 which engages under the extremity of the arm 25. The pivoted arm 27 can be swung out of the way when it is desired to oscillate the head-rest. The head rest has a handle 28 for oscillating it up and down.

The forward set of fingers 16 which engage the atlas are removably held in adjustable blocks 29, which are slidably mounted in a pair of brackets 30, which, in turn, are slidable toward and away from each other in guides in the cross slide 14. The blocks 29 which hold the fingers, are individually adjustable by means of adjusting screws 31, which are attached to them and threaded in the upper ends of the brackets 30.

The brackets are adjustable simultaneously by means of a right and left screw 32 horizontally held in the cross slide 14. The oppositely threaded ends of the screw 32 engage in threaded holes through the lower ends of the brackets 30. The second set of fingers 17 are held by blocks 33, which are adjustably mounted in the slide boxes 34 for horizontal adjustment toward and away from each other and for adjustment toward and away from the fingers 16.

The slide boxes 34 are mounted on the brackets 35 and are adjustable forward or backward by means of knurled screws 36. The brackets 35 are adjustable simultaneously toward and from each other by means of a right and left hand screw 37, which engages in threaded holes in their lower ends. The right and left screws 32 and 37 may be turned separately or simultaneously by means of the foot pedals 39 and 40 in order to leave the hands free for manipulating the clamping fingers and adjusting other portions of the apparatus.

Each of the right and left screws 32 and 37 has a spool 41 rotarily mounted upon its end next the knurled disk 38. The adjacent face of the spool is provided with ratchet teeth and adapted to be engaged by a spring-pressed detent 42. The spring-pressed detent 42 can be turned to engage the ratchet face of the spool 41 to slide over the teeth 50 in either direction, or it can be held out of engagement with the teeth.

Each spool 41 has a cord 43 wound upon it, the lower ends of the cords 43 being connected to the pedals 39 and 40, respectively, 55 so that by oscillating the foot pedals up and down, the spools 41 can be caused to oscillate around the right and left hand screw shafts 32 and 37 respectively. The small spiral springs 44 are arranged in annular recesses in the spools 41, one end of each spring being connected to the spool and the other end being connected to a fixed part of the cross slide 14. These spiral springs are under sufficient tension to keep the cords 43 60 taut and cause the spools to oscillate with

the foot pedal. By oscillating the foot pedal 39 and setting the detent 42 in the proper position, the screw shaft 32 can be rotated in either direction desired to adjust the brackets 30 toward or away from each other; 70 and the shaft 37 can be rotated in like manner by means of the foot pedal 40 to adjust the brackets 35.

In operating this invention or device, the patient reclines on a suitable support or 75 table, with his shoulders resting squarely upon its end, adjacent to the portable frame 10, and his head resting on the pad 20 of the head rest. The pad 20, plate 21 and strap 22 of the slide rests are adjusted to 80 hold the patient's head securely in position for the mechanical fingers to grasp or firmly hold the transverse processes of the patient's atlas and axis.

The front set 16 of fingers which holds 85 the atlas, and the rear set 17 which holds the axis, are adjusted toward each other simultaneously by means of the foot pedal, the operator using his fingers to guide them into proper position and making whatever 90 slight individual adjustments of the fingers may be required to suit the vertebrae of the patient. The sets of fingers may be operated by hand by turning the knurled disks.

After adjusting the fingers to clamp the 90 vertebrae securely, the operator turns the pivot arm 27 out of the way and slowly oscillates the head rest 18 up and down by means of the handle 28. The motion of the head is maintained for sufficient length of 100 time, depending upon the peculiarity of each individual case, and occasionally the fingers 16 and 17 are adjusted by the operator to bring the vertebrae gradually into proper alignment.

In some cases the motion of the head is unnecessary, it being sufficient to hold the head and body while the fingers 16 and 17 are moved vertically and horizontally to adjust the atlas and axis.

The invention is not restricted to the form of apparatus shown and described.

I claim the following as my invention:

1. A device of the character described having a set of clamps or fingers for simultaneously engaging the right and left transverse processes of the atlas, and a head rest pivoted to oscillate on an axis through said clamps for the atlas.

2. A device of the character described having a set of clamps or fingers for engaging the right and left transverse processes of the axis, a second set of clamps, said second set of clamps being arranged alongside of the first set for engaging the right and left 120 processes of the atlas.

3. A device of the character described having a set of clamps for engaging opposite sides of a vertebra, a second set of clamps, or fingers, arranged alongside of the first set, 130

and a head rest pivoted to oscillate transversely to the plane of said first set of clamps or fingers, the clamps in each set being independently adjustable with respect to each other.

4. A device of the character described having a set of clamps, or fingers, for engaging opposite sides of a vertebra, a second set of clamps, or fingers, arranged alongside of the first set, and a head rest pivoted to oscillate transversely to the plane of said clamps, the clamps in each set being independently adjustable in respect to each other, and the clamps of one set being adjustable toward and away from those of the other set.

5. A device of the character described having a set of clamps or fingers for engaging opposite sides of a transverse process of a vertebra of the neck, a second set of clamps arranged alongside of the first set to engage the right and left process of an adjacent vertebra of the neck, said clamps or fingers being independently adjustable toward and from each other, means for adjusting said clamps toward or from each other, and a head rest pivoted to oscillate vertically on an axis transverse to said vertebra and located adjacent thereto.

6. A device of the character described having a set of clamps or fingers for engaging opposite sides of the first vertebra of the neck, a second set of clamps arranged alongside of the first to engage the second vertebra of the neck, said clamps, or fingers, being independently adjustable toward and from each other, means for adjusting said clamps toward or from each other, and a head rest pivoted to oscillate about said first clamps or fingers, and foot operated means for adjusting the clamps or fingers of each set toward each other independently or simultaneously.

7. A device of the character described having a set of clamps or fingers for engaging the right and left side of the first vertebra of the neck, a second set of clamps arranged alongside of the first to engage the right and left side of the second vertebra of the neck, said clamps or fingers being independently adjustable toward and from each other, means for adjusting said clamps toward or from each other, and foot operated means for adjusting the clamps or fingers of each set toward each other independently or simultaneously, in combination with a table for supporting the shoulders of a patient, and a head rest adjustable vertically and horizontally with respect to said table.

8. A device of the character described having a set of clamps or fingers for engaging opposite sides of the first vertebra of the neck, a second set of clamps arranged alongside of the first for engaging opposite sides of the second vertebra of the neck, said clamps or fingers being independently ad-

justable toward and from each other, and means for adjusting the clamps or fingers of each set toward each other independently or simultaneously, in combination with a table for supporting the shoulders of a patient, a head rest adjustable vertically and horizontally with respect to said table and having clamps for the head vertically and horizontally adjustable with respect to the clamps or fingers for the vertebrae of the neck, said head rest being mounted for pivotal movement in a vertical plane around a horizontal axis adjoining said clamping fingers.

9. A device of the character described having clamps or fingers arranged in sets for engaging opposite sides of a transverse process of a vertebra of the neck, said clamps or fingers being independently adjustable toward and from each other, hand operated means for adjusting said clamps toward or from each other, and foot operated means for adjusting the clamps or fingers of each set toward each other independently or simultaneously, in combination with a table for supporting the shoulders of a patient, a head rest adjustable vertically and horizontally with respect to said table, and with respect to the clamps or fingers, said head rest being mounted for a pivotal movement in a vertical plane around a horizontal axis alongside of said clamping fingers, said head rest having a clamping means for securely holding the patient's head.

10. A device of the character described having a set of clamps or fingers for engaging the right and left side of a vertebra of the neck, said clamps or fingers being independently adjustable toward and from each other, foot operated means adjusting said clamps simultaneously toward or from each other, and a head rest pivoted to oscillate about said clamps or fingers, in combination with a table for supporting the shoulders of a patient in suitable position with respect to the clamps or fingers, said head rest having hand operated clamping means for securely holding the patient's head, whereby one operator can adjust said clamping means independently and simultaneously.

11. A device of the character described having a set of clamps for engaging opposite sides of a vertebra, a second set of clamps arranged alongside of the first set, and a head rest pivoted to oscillate transversely to the plane of said clamps, and foot operated means for adjusting clamps of each set toward each other independently and simultaneously.

12. In combination with a table for supporting the shoulders of a patient, a head rest adjustable vertically and horizontally with respect to said table, and clamping means for a vertebra of the neck adjustable with respect to said head rest.

13. In combination with a table for sup-

- porting the shoulders of a patient, a head rest adjustable with respect to said table, and clamping means for a vertebra of the neck adjustable with respect to said head rest, said head rest being mounted for pivotal movement in a vertical plane around a horizontal axis through said vertebra clamping means. 5
14. In combination with a table for supporting the shoulders of a patient, a head rest adjustable with respect to said table, said head rest having clamping means for securely holding the patient's head, and clamping means for a vertebra of the neck adjustable with respect to said head rest, said head rest being mounted for oscillation about said vertebra clamping means. 10
15. In combination with a table for supporting the shoulders of a patient, a head rest adjustable with respect to said table, said head rest having clamping means for securely holding the patient's head, and clamping means for a vertebra of the neck adjustable with respect to said head rest, said head rest being mounted for oscillation about said vertebra clamping means, and means whereby one operator can adjust all of said clamping means independently and simultaneously to the patient. 20
16. In combination with a table for supporting the shoulders of a patient, a head rest adjustable vertically and horizontally with respect to said table, and clamping means for a vertebra of the neck adjustable with respect to said head rest, said table, head rest and clamping means being connected for relative movement whereby the neck of the patient is alternately stretched and straightened. 30
17. A device of the character described having two sets of holders for fingers, suitable fingers mounted in said holders for clamping the vertebrae of the neck, a frame for supporting the head, said frame and holders being relatively movable. 45
18. In combination with means for supporting the shoulders of a patient, a head rest adjustable vertically and horizontally with respect thereto, and coöperating clamping means for engaging opposite sides of the 50 vertebrae of the neck, said clamping means being adjustable with respect to said head rest. 55
19. In combination with means for supporting the shoulders of a patient, a head rest adjustable with respect thereto, and co-operating oppositely disposed clamping means for a vertebra of the neck adjustable with respect to said head rest, said head rest being mounted for pivotal movement around 60 a point adjacent to the axis of said vertebra clamping means. 60
20. In combination with means for supporting the shoulders of a patient, a head rest adjustable with respect thereto, said head rest having clamping means for securely holding the patient's head, and clamping means for securely holding a vertebra of the neck adjustable with respect to said head rest, said head rest being mounted for oscillation about said vertebra clamping means. 70
21. In combination with a table for supporting the shoulders of a patient, a head rest adjustable with respect to said table, said head rest having clamping means for securely holding the patient's head, adjustable clamping means for securely holding a vertebra of the neck, said vertebra clamping means being adjustable with respect to said head rest and table, and means whereby one operator can adjust said clamping means independently and simultaneously. 75
- Signed at St. Louis, Missouri, this 17th day of June, 1916.

ADRIAN D. NICHOLS.
